UNITED STATES PATENT OFFICE.

JAMES H. ROGERS, OF WASHINGTON, DISTRICT OF COLUMBIA, ASSIGNOR,
BY MESNE ASSIGNMENTS, TO THE AMERICAN ELECTRO GAS TELEPHONE
COMPANY, OF NEW JERSEY.

APPARATUS FOR TELEPHONIC COMMUNICATION.

SPECIFICATION forming part of Letters Patent No. 268,366, dated November 18, 1883.

Application filed November 8, 1880. (No model.)

To all whom it may concern:

Be it known that I, JAMES HARRIS ROGERS, a citizen of the United States, residing at Washington, in the District of Columbia, have invented certain new and useful Improvements in Apparatus for Telephonic Communication, of which the following is a specification.

My invention relates to means and appliances for the transmission of sound-waves through gas-pipes for the purpose of communicating speech from one part of a building to another, and also to suitable appliances for conveying impulses through gas-pipes to produce call-signals without permitting the escape of gas.

The invention is designed, chiefly, for domestic purposes, to be used in lieu of speaking-tubes, electric bells, annunciators, and so forth, by the employment of the gas-pipes of buildings as a means of communicating audible and intelligible sounds, so that every apartment in a house to which the gas-pipes extend may be signaled, and a person in one apartment may speak to another in any other apartment. It is applicable to dwellings, hotels, business houses, and public and other buildings of any size.

My invention relates to that form of telephonic apparatus in which vibratory diaphragms of thin metal or other material are stretched or placed across suitable openings in communication with the gas-pipes, and so sealed or packed as to prevent the escape of gas to any material extent, so that vibrations produced by the voice on one of such membranes may be transmitted through the gas in the pipes to a similar membrane applied to another aperture in connection with said pipes in a different part of the building. Any convenient prolongations of the pipes are used, suitably shaped at their terminations to adapt them for application to the mouth and ear of persons using them for speaking and hearing.

My invention consists, first, in the provision of flexible or movable pipes connecting the transmitting and receiving instruments with the gas-pipes to render the said instruments more convenient to handle; and, secondly, in the combination, with the gas-pipes,

of a bell or whistle or other call-signal to be actuated by an impulse or vibration conveyed through the gas in the pipes and transmitted through a liquid trap, the liquid serving to transmit sufficient movement to the air beyond to sound the whistle or work any mechanical contrivance employed to ring a bell, while at the same time preventing the escape of gas.

In the accompanying drawings, Figure 1 is a sectional view illustrating two stations or instruments connected by gas-pipes and adapted for use in different apartments, and branch pipes which may communicate with similar instruments in other apartments. Fig. 2 is a sectional view of a modification in the construction of the call-signal, in which the liquid in the trap acts on a bell-hammer through the medium of a float, as hereinafter described.

N N' represent mouth and ear pieces, which may be of any suitable and convenient form, and M M' diaphragms of thin metal or other elastic material stretched or applied across the mouths or openings thereof, so as to transmit or receive sound-waves.

G G' represent the gas-pipes, and T T' the hollow stems of the transmitting and receiving instruments, connected through flexible tubes I I' with the gas-pipes G G', so that the gas in said pipes will be in contact with the inner surfaces of the membranes M M'. The flexible pipes I I' render the transmitting and receiving instruments convenient to handle.

Call-whistles such as are commonly used in the mouth-pieces of speaking-tubes are placed at W W', and liquid traps at X X', to prevent the escape of gas through the same.

In Fig. 2 I have shown as a modification a float, V, resting on the liquid in the trap, and supporting a rod, Y, provided with a hammer, y, which by an impulse imparted to the liquid in the trap by pressure in the gas-pipe will be made to strike the bell Z. As speaking-tubes are commonly provided with mouth-pieces containing call-whistles to be sounded by a blast of air produced through a similar mouth-piece at a distant point, and such mouth-pieces and call-whistles are perfectly applicable to the carrying out of the second

part of my invention, no representation or specific description of such means of producing the blast or pressure within the pipes is necessary; but it is only requisite to show and 5 describe the liquid traps X X', which I have devised to permit the use of such call-whistles in connection with gas-pipes. It is self-evident that pressure applied to the liquid trap X at one station will throw the liquid tempo- 10 rarily out of equilibrium, producing pressure in the gas-pipe G, which pressure will be trans- mitted to the liquid in the trap X' at the other station, throwing the liquid therein tempo- 15 rarily out of equilibrium and driving a blast of air through the whistle W'. It is no objection to the apparatus that a blast continued long enough to drive the liquid completely out of and beyond the trap-bends would result in driving a small quantity of air into the gas- 20 pipes and a corresponding quantity of gas into the atmosphere, because this would in no case be sufficient in amount to cause any inconveniences, and in practice the traps will be of sufficient depth and size to prevent the 25 ejection of the liquid therefrom by ordinary lungs. The instant the pressure is removed the liquid in all the traps resumes its level as nearly as the normal pressure of the gas will permit, the excess of air within the pipe es- 30 caping through the whistle or mouth-piece W, and air entering through the whistle W' to take the place of that which was ejected through the same. By the use of the modification shown in Fig. 2 the movement of the liquid in the 35 trap X' is made to act through a float on a

bell-hammer, and it is evident that a person desiring to call another may produce the necessary motion of the gas in the pipe by a sudden depression of the float at his own station. When one speaks at N, Fig. 1, the words are 40 conveyed to N', and to every other aperture similarly covered with a vibrating membrane in all the gas-pipes, so that one listening at N' will hear what is said at N, and, vice versa, one at N will hear what is said at N'. 45

Having thus described my invention, the following is what I claim as new therein and desire to secure by Letters Patent:

1. The combination of the gas-pipes of a building, suitable flexible or movable pipes 50 connected therewith, and flexible membranes stretched or applied over suitable apertures in said flexible or movable pipes, so as to confine the gas therein, while permitting the passage of sound-waves. 55

2. The combination of a gas-containing pipe, a vibrating membrane in contact with the contained gas, a liquid trap connected with the gas-pipe, and a suitable sounder in communication with the trap, but separated from the 60 gas by the liquid in said trap. 60

3. In a gas-telephone, a liquid receptacle or trap and a signaling device in communication therewith, operated by impulses applied through the medium of the liquid in the trap, 65 substantially as set forth.

JAS. HARRIS ROGERS.
